NONREGENERATIVE RADIO CIRCUITS

Application filed April 17, 1924. Serial No. 707,150.

This invention relates in general to audion circuits as used, for example, in radio communication and other electrical arts in which a grid or control electrode governs the flow of electron current from a heated filament or cathode to a plate or anode. A primary object of the invention is to control the regenerative tendency of audion tubes or circuits by reducing the effect of electrostatic coupling between grid and plate electrodes and prevent generation of oscillations.

In many of the uses to which the audion is adapted and applied, the electrostatic capacity between plate and grid electrodes (together with their respective leads) gives rise to a transfer of plate circuit energy to the grid circuit when a change in the strength of the plate current occurs, and when this energy transfer occurs in proper phase relation with a change in grid potential, the effect will be to add to the change of grid potential and give rise to the familiar regenerative action within the audion and its circuits. The effect is subject, of course, to quantitative considerations involving the constants of the circuits, the design of the audion, and the frequency or rapidity at which the change in grid potential occurs. In general, it is favored by low resistance, high electrode capacity, and high frequency. These factors may be such as to permit the system to act as an independent generator of oscillating current, which often is detrimental to the purpose intended. For example, the employment of tuned radio frequency amplifier stages in radio receivers is often accompanied by considerable difficulty due to the tendency of the system to generate oscillations when the circuits are tuned to approximate resonance, and this tendency may be such as to prevent the designing of the receiver on the most efficient lines.

The invention is based upon the principle of reducing or substantially eliminating the coupling between plate and grid circuits by interposing between these circuits an inductive impedance. By placing the impedance in the grid return lead, which is here understood to be the lead between the filament and the grid circuit inductance or closed oscilla-

tory circuit of the grid filament circuit, the proper flow of plate current through the plate-filament circuit is in no way interrupted. Likewise the grid, being a voltage operated element, may continue to perform its normal function without impairment, provided the impeding element is not of such nature or value as to adversely affect the normal grid to filament voltage.

The nature of the invention may be clearly understood with reference to the accompanying diagrams illustrating the use of the invention in various circuits. While the invention is not limited to the radio art, we may assume for the sake of clearness that these circuit diagrams represent certain standard radio circuits in common use today, with the impedance element inserted for controlling the regenerative tendency of the audion.

In said drawing:

Figure 1 is a diagram of an untuned radio frequency amplifier stage.

Figure 2 represents a tuned radio frequency amplifier stage.

Figure 3 shows a receiver system including one stage of tuned radio frequency amplification, a tuned detector, and one or more stages of audio frequency amplification.

Referring in detail to Figure 1 of the drawing, 10 indicates the grid, 11 the plate and 12 the filament of an audion. A primary coil 13 of a radio frequency transformer is located in the plate circuit and connected by conductor 14 to the plus side of B-battery 15, the negative terminal of which is connected to the plus side of the A-battery 16. The filament 12 is connected by conductor 17 with the plus terminal of A-battery 16 and minus terminal of B-battery 15, thus completing the plate filament circuit. A rheostat 18 is connected with the other terminal of filament 12 and through the arm 19 is connected with the minus terminal of the A-battery 16. The filament system is thus completed. The grid 10 is connected by conductor 20 with the secondary coil 21 of a coupling transformer, the lower terminal of which is connected by conductor 22 with one end of an inductive impedance element 23, whose other end is connected by conductor 24 with the minus termi-

nal of the A-battery 16. This completes the grid filament system. The conductors 23 and 24 here constitute the grid return lead. Coil 21 represents, by way of example, an element in the grid filament circuit, by which voltage variations are imparted to the grid electrode. The impedance 23 is an inductive impedance and is thus conductive to direct current. Its value will depend upon the extent to which it is desired to limit the electrostatic coupling effect existing between grid 10 and plate 11 of the audion for the particular system in which it is employed. The function of the impedance may be clearly understood on the theory that an electrostatic influence of the plate potential upon the grid potential depends upon the transfer of electrons from plate to grid or vice versa and that the extent to which this transfer may occur is dependent partly upon the impedance which the electrons encounter in their travel through, what may be termed, the plate grid circuit. It will be noted that this circuit is normally completed through the unobstructed junction between plate-filament system and grid-filament system, but that in accordance with the present invention, the high frequency transfer of electrons is impeded by the high inductive reactance of the element 23, which does not, however, interfere with the normal current in the plate-filament circuit or the proper voltage variation in the grid circuit. As an inductive reactance or impedance element, I have found satisfactory, an iron cored choke coil comprising in the neighborhood of one thousand to fourteen hundred turns of about No. 30 enameled wire upon a soft iron core one-quarter of an inch in diameter and about one inch in length occupied by the turns.

The impedance element 23 should not be of such value or connected in such manner as to have any substantial effect in causing a departure of the grid potential from the desired normal value. At higher frequencies a higher impedance is necessary on account of the smaller capacitative impedance of the grid and plate electrodes in the tube. By the use of an inductive impedance, the opposition to regeneration automatically increases at the higher frequencies. In the design of the inductive impedance, care must naturally be exercised in avoiding undue distributed capacity so that within the frequencies contemplated, the impedance will retain a sufficient preponderance of inductive reactance.

From the above general description of the nature and function of the impedance 23, its use in other types of circuits will be readily understood.

Referring to Figure 2, the circuit is substantially the same as that shown in Figure 1, with the exception that here the secondary coil 21 has the tuning capacity or condenser 25 connected in parallel therewith forming a

closed oscillatory circuit, to one side of which the grid electrode 10 is connected and to the other side of which the impedance 23 is connected, the conductor 24 constituting the grid return lead from the closed oscillatory circuit 21, 25 to the negative terminal of the A-battery, and having inserted therein the impedance 23 as before. The voltage oscillation in the closed oscillatory circuit 21, 25 is not opposed by the impedance 23, as the latter is outside of the closed circuit, but the normal functions of the audion occur without the usual tendency to regenerate and produce oscillations.

Figure 3 illustrates in principle the application of the invention to a receiving set employing radio frequency amplification, a tube detector, and audio frequency amplification. In this case the antenna inductance 60 is coupled with the inductance 21, across which is the tuning capacity 25, to one side of which the grid 61 is connected and to the other side of which the choke coil 23 is connected. Choke coil 23 is here again interposed in the connection from the closed oscillatory circuit of the grid which leads to the negative lead 62 of the A-battery 63. The detector circuit is illustrated as comprising the closed oscillatory circuits 64, 65, grid condenser 66, grid leak 67, grid 68 and grid return lead 69 to the filament 70. The output from plate 71 passes through primary 72 of an audio frequency transformer, whose secondary 73 is connected to the grid 74 of the audio amplifier tube. Detector B-battery lead 75 connects the primary coil 72 with the B-battery 76 at the desired tap, the negative terminal of the B-battery being connected to the plus terminal of the A-battery. The various battery leads and circuit connections are of standard present-day practice and need not be specifically described. The use of the impedance 23 interposed in the grid return lead enables the radio frequency amplifier to be tuned to maximum amplification without fear of oscillation occurring from the inter-electrode capacity of the grid and plate elements. The detector tube being ordinarily operated on much lower voltage than that of the amplifier tubes and having the output connected through an untuned audio frequency transformer, will not ordinarily require the use of the impedance 23, although, of course, the same may be employed in the detector circuit, if desired.

The above description with reference to a number of different examples of the use of the invention will enable those skilled in this art to understand and practice the invention. No attempt has been made to illustrate all of the great variety of circuits in which the impedance element 23 may be used to advantage. The value of the impedance referred to may be varied to meet different requirements, but the values which I have given

above, by way of example, have been found in practice to be sufficient to prevent the generation of oscillations in the audion tube and its associated circuits, in the case of high vacuum tubes of relatively high internal plate grid capacity, such as those marketed under the designation "UV201-A Radiotron". Such tubes have been successfully employed in all of the circuits illustrated and in similar circuits in which a plurality of stages of radio frequency amplification were utilized.

I claim:—

A radio frequency amplifier circuit comprising an audion with input and output circuits tending to produce regeneration through the plate-grid capacity of the audion, said input circuit having connected between grid and filament a variable radio frequency tuning circuit comprising an inductance element shunted by a condenser, for imparting at variable radio frequencies a voltage between grid and filament, and a choke coil interposed in the connection of the filament to said tuning circuit, the inductive reactance of said choke coil sufficiently predominating, at the radio frequencies to which said tuning circuit may be tuned, to substantially check the feed back of radio frequency energy from the output circuit to the input circuit through the plate-grid capacity.
